UNITED STATES PATENT OFFICE.

STAFFORD F. SUTHERLAND, OF PHILADELPHIA, PENNSYLVANIA, ASSIGNOR TO
SUTHERLAND COLLAPSIBLE PAPER BOX COMPANY, OF PHILADELPHIA, PENN-
SYLVANIA, A CORPORATION OF DELAWARE.

COLLAPSIBLE FOLDING BOX.

1,425,068.

Specification of Letters Patent. Patented Aug. 8, 1922.

Application filed February 25, 1921. Serial No. 447,665.

To all whom it may concern:

Be it known that I, STAFFORD F. SUTHERLAND, a citizen of the United States, residing in the city and county of Philadelphia and State of Pennsylvania, have invented certain new and useful Improvements in Collapsible Folding Boxes, of which the following is a specification.

My invention relates to folding boxes and especially to that type known as collapsible boxes, and the object of my invention is to provide an improved box of this character, that is simple in construction, inexpensive of manufacture and can be very easily and very quickly set up—that is, erected in box form—and is securely held in erect position, after it is set up.

The objects and advantages of my improved box, will be readily apparent in this specification when taken in connection with the accompanying drawings, in which—Fig. 1, is a blank of which the box-body is formed. Fig. 2, is a locking-flap. Fig. 3, is a view of the complete box-body in its flat or collapsed form. Figs. 4 and 5 are views of an end section of the box-body showing two stages, in the operation of setting it up. Fig. 6, is a view of the box-body fully set up. Fig. 7, is a view of an end section of the box-body, fully set up, and has a part of the locking-flap torn away. Fig. 8, is a blank, of which the box-cover is formed. Fig. 9, is a view of the complete box cover, in its flat, or collapsed form. Fig. 10, is a view of an end section of the box-cover, set up. Fig. 11^a, is the locking-flap (Fig. 2) slightly modified. Fig. 11, is the blank (Fig. 1) with the locking-flaps to be attached. Fig. 11^b, is the staple (enlarged) used for attaching the locking-flap to the end-wall of the box. Fig. 12, is a view of the complete box-body in its flat form, and shows the locking-flap attached with staples. Fig. 13, is an end section of a modified form of the blank. Fig. 14, is an end section of this box (Fig. 13) in its flat form. Fig. 15, is a single blank of which both the box-body and the box-cover are formed. Fig. 16, is a view of the complete box (Fig. 15) in its flat form. Fig. 17, is a view of this box (Fig. 16) set up. Fig. 18, is a view of this box (Fig. 17) closed. Fig. 19, is the blank (Fig. 15) slightly modified, of which both body and cover of the box, are formed. Fig. 20, is a view of the

complete box (Fig. 19) in its flat form. Fig. 21, is a view of this box (Fig. 20) set up.

Referring to the drawings; Fig. 1 is a blank of which the box-body is formed, and is a single piece of paper-board or other suitable material, and it is creased or scored at the dotted lines 2, longitudinally, at the dotted lines 3 transversely, and at the dotted lines 4 diagonally, so as to facilitate the bending or folding of its various parts at these lines, in forming the body; and this blank comprises the following foldable parts, namely—the bottom A, opposite side-walls B, opposite end-walls C, and corner-folds D integral with and connecting the side-wall and the end-walls and this corner-fold D comprises two triangular sections D¹ and D². In making this box-body, the blank is folded longitudinally at the lines 2, the side-walls B folding on the bottom A and the corner-folds D on the end-walls C, as shown in Fig. 3, and a separate locking-flap E, shown in Fig. 2, is then placed on each end-wall C, over the corner-folds, and is attached to the end-wall, by sewing or stitching it to the wall, along the outer, or free edge 9 of the wall at the dotted line 8, as shown in Figs. 3, 4, 5, and 6; the sewing or stitching being done by a sewing-machine, the thread passing through the outer edge of the triangular section D¹ of the corner-fold and thus holding that section to the end-wall and allowing the other triangular section D², to fold freely under the locking-flap and below the stitching, while the box-body is being set up. This will be more clearly understood by referring to Fig. 7, which is a view of an end section of the box-body, set up, and shows a portion of the locking-flap E torn away; and it will be seen that the triangular section D¹ of the corner-fold is held to the end-wall C by the stitching 8, but the upper edge 6 of the triangular section D² is below the stitching and is therefore free to move back or forth under the locking-flap, as the box is collapsed or set up. As the locking-flap extends very nearly to the bottom of the box, it therefore holds the box securely in erect position when it is set up, and when it contains goods, the goods will hold the flap against the wall and the box-body cannot collapse until the goods are taken out; also as the locking-flap is cut out separately

and attached to the end-wall, both flap and blank can therefore be cut out with no waste of material, whereas there will be considerable waste of material if the flap is an integral part of the blank, cut out with the blank; and moreover the locking-flap can be of a lighter, more flexible and cheaper material than the blank, and this will not only lessen the cost of the box, but will also 10 permit the box to be set up more easily and more quickly. When the box in its flat form (Fig. 3,) has to be set up, it is only necessary to grasp both end-walls and push them to an erect position, the side-walls 15 moving automatically to an erect position also; or grasp both side-walls and pull them to an erect position, the end-walls moving automatically to an erect position also; but in either case the triangular section D² of 20 the corner-fold, will very easily and very quickly fold back against the other section D¹ and the locking-flap will very easily and very quickly move over this triangular section, to an erect position on the inner side of 25 the end-wall and thus securely hold the box-body in its erect position. The very easy and very quick way in which the box may be set up, will be more fully understood by referring to Figs. 4 and 5, which are views 30 of an end section of the box-body and show two stages in the operation of setting it up. In Fig. 6, the box-body is shown set up. Fig. 8, is a blank of the box-cover, and it is practically the same as that of the body 35 blank (Fig. 1) but the end-walls are deeper than the side-walls—the depth of the end-wall C from the dotted line P to its base is the depth of the side-wall B. This cover blank is folded longitudinally at the dotted 40 lines 2, and the locking-flap E is attached to the end-wall C by stitching it along the edge 9 of the wall at the dotted line 8, as shown in Fig. 9, which is the complete box-cover in its flat form, and it is set up 45 in the way I have already described. Fig. 10, is a view of an end section of this box-cover, set up. The separate locking-flap E (Fig. 2) may be attached to the end-wall by other means, than that of stitching it 50 with a sewing machine; it may be attached by hand or by a machine, stitching it to the end-wall, along its outer or free edge 9, and using wire staples F, as shown in Fig. 12. A staple F (Fig. 11^b) is used at each end 55 10 of the flaps E near the outer edge 9 of the wall, and as many more staples F as may be necessary between these two end staples all along the edge of the wall. The locking-flap E may be wider and creased, scored, slit 60 or folded at the dotted line 11 as shown in Fig. 11^a and placed at the ends of the blank Fig. 11, (which is the same as blank Fig. 1) with the narrow part 12 on the end-wall C, and the blank is then folded longitudinally 65 at the dotted lines 2 and the outer

part 13 of the locking-flap folded on the corner-folds and end-wall, and attached to the wall with staples, along the edge 9 of the wall, as shown in Fig. 12. The ends of these old and well known staples pass 70 through the parts and are bent and clinched on the other side in the old and well known way.

Fig. 13, is an end section of a blank that may be used instead of the blank before described. This blank is slit at G which disconnects the end wall and the corner-folds and it is folded at the dotted lines 2, with the section D³ under D⁴ of the corner-fold and the locking-flap E is then stitched to 75 the end wall as shown in Fig. 14. Fig. 15, is a single blank of which the box-body and box-cover are formed. It is scored or creased at the dotted lines 14 longitudinally, at the dotted lines 15 transversely, and at 80 the dotted lines 16 diagonally. It comprises the following foldable sections, namely—the body bottom H, the body side-walls J, the body end-walls K and K¹, the body corner folds L, the body corner-flaps 85 M, the cover top N, the cover side-walls O, the cover end-wall P and the cover corner-folds R. The body corner-fold L comprises the triangular section L¹ and L² and the cover corner-fold R comprises triangular 90 sections R¹ and R². Slots S are made in the body side-walls. This blank is folded longitudinally at the dotted lines 14, the parts of the body, namely, side-walls J folding on the bottom H, corner-folds L on 100 end-wall K and corner-flaps M on end wall K¹ and the parts of the cover, namely, side-walls O folding on the top N and corner-folds R on end-wall P and locking-flaps E (Fig. 2) are attached to the outer end-wall 105 K of the box and the end-wall P of the cover, as shown in Fig. 16, which is the complete box in its flat or collapsed form. In this case the locking-flap is stitched to the end-wall by a sewing machine, along the 110 outer edge of the wall, at the dotted line 8; but it may be attached by means of staples as before described and shown in Fig. 12. This box is set up for use by simply pulling the side-walls of both body and cover, to an 115 erect position and the other foldable parts will automatically move to their proper set up positions, as before described and shown in Figs. 4 and 5. The corner flaps M are then turned in and the box is ready to receive the goods. In Fig. 17, this box is 120 shown set up; and in Fig. 18, it is shown closed, with the free corners T of the side-walls of the cover, inserted in the slots S of the side-walls of the body. The blank 125 Fig. 19, is a slight modification of the blank Fig. 15. The only difference between the two blanks, is that in the Fig. 19 blank the corner-folds L are substituted for the corner-flaps M of the Fig. 15 blank; but in all 130

other respects they are both the same; and this blank (Fig. 19) is folded longitudinally at the dotted lines 15, the same as the other; but locking-flaps E are attached to both 5 end-walls K and K¹ of the body and also the end-wall P of the cover. The locking flaps are attached in the way before described and shown. Fig. 20 shows the complete box in its flat form, and it is set up in 10 the way already described and shown. Fig. 21, shows this box, set up.

Having thus fully described my invention, I claim—

1. A collapsible box having a bottom, 15 foldable side walls connected to the bottom, foldable end walls also connected to the bottom, corner folds connected with the side and end walls and comprising foldable triangular sections, and separate flexible 20 locking flaps attached to the end walls along the free edge of the wall.

2. A collapsible box having a bottom, 25 foldable side walls integrally connected to the bottom, foldable end walls also integrally connected to the bottom, corner folds connected with the side and end walls, and separate flexible locking flaps of substantially the same dimensions as the end walls and connected thereto at the extreme outer 30 edge thereof.

3. A collapsible box having a bottom, 35 foldable side walls connected with the bottom, foldable end walls also connected with the bottom, corner folds connected with the side and end walls and comprising foldable triangular sections, and separate flexible locking flaps of substantially the same dimensions as the end walls and stitched thereto at the extreme outer edge thereof.

4. A collapsible box having a bottom, 40 foldable side walls connected with the bottom, foldable end walls also connected with the bottom, corner folds connected with the side and end walls, and separate flexible locking flaps connected to the end walls by 45 stitching staples along the outer edge thereof.

5. A collapsible box having a box body and a box cover integrally connected, the box body comprising a bottom, foldable 50 side and end walls connected with the bottom, the box cover comprising a top, folded side and end walls connected thereto, and locking flaps attached to the end walls of the body and one end wall of the cover 55 along the outer edge of said wall.

6. A collapsible box having a box body and a box cover integrally connected, the box body comprising a bottom, foldable side and end walls connected with the bottom, 60 and corner folds connected with the side and end walls, the box cover comprising a top, foldable side and end walls connected thereto, and locking flaps attached to the end walls of the body and one end wall of 65 the cover at the outer edge of said wall.

7. A collapsible box having a box body and a box cover integrally connected, the box body comprising a bottom, foldable side and end walls connected with the bottom, 70 the cover comprising a top, foldable side and end walls connected thereto, and locking flaps attached to the end walls of the body and one end wall of the cover, the side walls of the body being provided with slots 75 to receive the free corners of the side walls of the cover.

STAFFORD F. SUTHERLAND.
